No. 36,458.

Patented July 21, 1903.

UNITED STATES PATENT OFFICE.

PHINEAS B. MYERS, OF MORRISTOWN, NEW JERSEY.

DESIGN FOR A PAPER BOX.

SPECIFICATION forming part of Design No. 36,458, dated July 21, 1903.

Application filed June 24, 1903. Serial No. 162,971. Term of patent 3½ years.

To all whom it may concern:

Be it known that I, PHINEAS B. MYERS, a citizen of the United States, residing at Morristown, Morris county, New Jersey, have invented a new, original, and ornamental Design for Paper Boxes, reference being had to the accompanying drawing, which represents a perspective view of a paper box showing my new design.

What I claim is—

The ornamental design for a paper box, substantially as shown.

Signed by me at New York city, (Manhattan,) New York, this 23d day of June, 1903.

PHINEAS B. MYERS.

Witnesses:

WILLIAM SCHULZ,
FRANK V. BRIESEN.
